UNITED STATES PATENT OFFICE.

OLIVER R. VEGELY, OF CHICAGO, ILLINOIS.

GOLF-TEE.

1,251,944.

Specification of Letters Patent.

Patented Jan. 1, 1918.

Application filed August 11, 1917. Serial No. 185,752.

To all whom it may concern:

Be it known that I, OLIVER R. VEGELY, a citizen of the United States, residing at Chicago, in the county of Cook and State 5 of Illinois, have invented certain new and useful Improvements in Golf-Tees, of which the following is a specification, reference being had to the accompanying drawings.

This invention relates to golf tees, and 10 particularly to that class of tees which are intended to be carried in the pocket of the player and used from time to time as circumstances require.

The general object of the invention is to 15 provide a very simple tee, which may be cheaply made, which is easily carried, and which is entirely effective for the purpose intended.

Other objects will appear in the course of 20 the following description.

My invention is illustrated in the accompanying drawings, wherein:—

Figure 1 is a perspective view of a pair 25 of my improved tees; and

Fig. 2 is a vertical sectional view through one of the tees showing the golf ball in place thereon.

As will be seen by the drawing, my improved tee consists of a strip of relatively 30 thick felt, or like material, which is designated 10, this strip being folded upon itself and the ends of the strip being connected to each other preferably by means of a slip knot 11, formed in a cord or tape 12. This 35 cord or tape is preferably double and preferably attached to the opposite end of this flexible connection formed by the cord or tape is another tee 10 of the same character as the first one. Ordinarily and when not 40 in use, these tees 10 will be flat and approximately in the shape shown on the righthand side of Fig. 1. When the tee is to be used, however, the end of the tee opposite the joined extremities thereof is forced inward

so as to laterally expand the tee and in this 45 position it may be readily set upon the ground and will support the ball as shown in Fig. 2. The tee is, of course, used in the ordinary manner and because of its lightness it will fly but a short distance if it be 50 struck by the club and therefore requires no anchor as do many forms of tees. It will be seen that if a tee becomes worn, it may be very readily removed and a new tee fastened to the tape 12. The tees may be very 55 cheaply made and are thoroughly effective.

While I have referred to felt as being the material of which the tee is made, it is obvious that other materials having a certain amount of stiffness may be used. 60

Having described my invention, what I claim is:—

1. As an article of manufacture, a golf tee formed of a strip of relatively thick fibrous material bent upon itself and having 65 its ends connected.

2. As an article of manufacture, a golf tee formed of a strip of felt folded upon itself and having its ends connected.

3. As an article of manufacture, a golf 70 tee comprising a strip of flexible relatively heavy material folded upon itself, and a tape detachably engaging the ends of the folded strip.

4. As an article of manufacture, a pair of 75 conjoined tees, each consisting of a strip of flexible relatively heavy fibrous material folded upon itself, and a double tape having slip knots formed at its ends, these slip knots engaging with each of said tees and holding 80 the extremities of the strips together.

In testimony whereof I hereunto affix my signature in the presence of two witnesses.

OLIVER R. VEGELY.

Witnesses:

HORACE M. COOLING,
S. MICKLE.
